LIQUOR DECANTER

Thomas Merrill, 426 S. Roosevelt Ave., Pasadena, Calif.

Filed Oct. 29, 1959, Ser. No. 58,110

Term of patent 14 years

(Cl. D58—9)

FIG. 1

FIG. 3

Fig. 1 is a front elevational view of a liquor decanter, showing my new design;

Fig. 2 is a side elevational view thereof; and
Fig. 3 is a top plan view thereof.

The side not shown is the same as the side shown. The rear not shown is plain. The dominant features of my design reside in the portions shown in full line.

I claim:

The ornamental design for a liquor decanter, as shown and described.
